UNITED STATES PATENT OFFICE.

GEORGE P. BRAND, OF NEW YORK, N. Y.

VALVE MECHANISM FOR PNEUMATICALLY-OPERATED MUSICAL INSTRUMENTS.

1,247,604.

Specification of Letters Patent. Patented Nov. 20, 1917.

Application filed March 28, 1917. Serial No. 157,928.

To all whom it may concern:

Be it known that I, GEORGE P. BRAND, a citizen of the United States, and a resident of New York, in the county of the Bronx and State of New York, have invented certain new and useful Improvements in Valve Mechanism for Pneumatically-Operated Musical Instruments, of which the following is a specification, reference being had to the accompanying drawings, which form a part thereof.

The invention relates to musical instruments and more particularly to the action chest and valve mechanisms employed for actuating the player or power pneumatics.

The object of the invention is to provide a very condensed form of structure which may be readily and accurately assembled, and in which the various valve mechanisms and their elements are accessible.

A further object is to provide a valve mechanism which will act with great certainty and rapidity, and which may be assembled within the action chest and in and upon one wall of said chest in co-operative relation with striker or power pneumatics mounted exteriorly of the chest.

It has for a further object to provide an improved form of pouch or diaphragm, or primary pneumatic construction so as to obtain greater freedom of movement of the diaphragm to augment its delicacy and increase its power. I obviate the resistance inherent in the usual form of annular diaphragms by making the same substantially rectangular with but two supporting sides offering resistance, the other sides being practically free and unsupported.

The invention, as hereinafter illustrated, shows a player action of a unit form providing a very compact structure which may be placed in an instrument directly behind the "fall" board where ordinarily there is a limited space. The advantages of its condensed form are, therefore, apparent.

Still a further object of the invention is to provide simple, yet efficient means for muffling the sound or noise usually made by the valves and the air when in operation.

Referring to the drawings:

Figure 1 is a view in elevation of a por-

tion of the action chest with the front board broken away.

Fig. 2 is a vertical cross-section, on enlarged scale, through the action chest illustrating the connection of the player or power pneumatics with the wippines of a piano action.

Fig. 3 is a horizontal section through one tier of valve actions and appurtenant parts.

Fig. 4 is a perspective view of the pouch or primary pneumatic.

Fig. 5 is a perspective view of the component parts of the pouch illustrated in Fig. 4, said parts being disassembled.

Like numerals of reference indicate like parts in the several views.

Referring to the drawings,

1 denotes a suction and action chest which may be formed in any convenient manner and, as illustrated, has a rear supporting wall 2 for the valve actions and player pneumatics, a removable front wall 3 to give access to the chest 1, a base 4, end blocks 5 (which are shown in Fig. 3), and a head block 6.

Suction or pressure for the chest 1 is produced in any well known manner by apparatus not herein shown, the connection to the chest being preferably made through a channel 7 formed in the end blocks.

The head block 6 is formed in sections 8, 9.

The section 8 has borings, as at 10, which, through ducts 11, connect with the tracker-board of the instrument. The section 9 has borings 12 which register with the borings 10, and also has intersecting borings 13, which, through suitable conduits 14, connect with the primary pneumatics or pouches of the valve actions.

Upon the exterior of the back wall 2 of the chest are arranged supporting bars or ledges 15, of sectional form which support the striker pneumatics 16. As illustrated, there are three supporting ledges extending from end to end of the chest and which support three tiers of striker or power pneumatics. Each of the supporting bars or ledges has a base section 17, and an outer section 18, suitably secured together and secured to the wall 2.

The joints between the sections of the

head block and the sections of the supporting bars have suitable gaskets. There is a distinct advantage in forming these parts in section as they may be more readily bored 5 and more readily assembled.

Formed in the inner face of the wall 2 are valve chambers 19, there being a valve chamber with its valve mechanism for each of the striker pneumatics 16. Each valve 10 chamber has an atmospheric port 20, and each row or tier of valve chambers connects through its respective ports 20 with a channel 21, formed in the base 17 of the supporting bar, said channel being connected with 15 the atmosphere through borings 22. This arrangement provides an efficient muffling, as pressures are equalized, and also provides for very economical manufacture. It is well known that valves make a noise in moving 20 from one seat to another. After a pneumatic is deflated by the closing of the atmosphere port and upon release of the pneumatic by reason of the valve opening the inflation port and closing the exhaust port, 25 the air required to inflate the pneumatic causes an air noise in passing through the space between the valve and its seat, and it is desirable to dispense with this noise as much as possible. By the present construction 30 this is accomplished by deadening the sound so that it cannot be heard outside of the instrument. The bases 17 may be bored, as at 23, to correspond with the ports 20, and when grooved give a maximum 35 of area for passage of the air without materially diminishing the strength of the base-piece. Borings 24, formed through the outer face of the wall 2, intersect the valve chambers 19 at one side. These bor- 40 ings 24 register with openings 25, which are formed in part in the base-piece 17 and in part in the outer section 18 as seen in Fig. 2. Intersecting borings 26 connect them with the player pneumatics 16.

Arranged in the base-piece 17 are valve 45 pins 27, which extend centrally through the ports 20, and support the valves 28. Said valves 28 are freely movable upon the pins and serve to control the exhaust ports 20 and the suction ports 29, the latter being 50 formed through plates 30, which form exhaust valve seats for the valves and which are applied to the inner side of the wall 2. Each of the valves 28 has a stem 31 55 which is actuated by the diaphragm member 32 of the pouch of primary pneumatic 33.

The pouch or primary pneumatic 33 is of unique form and consists of a rectangular block 34 having a channel 35 which provides heads 36 over which the diaphragm member may be disposed. It is centrally bored as at 37, and upon the outer face of the block the boring is covered with a disk 38, cen-

trally of which there is a perforation 39 65 serving as a bleed hole.

The diaphragm member 32 is placed over the block 34 and upon the heads 36, being secured by glue or the like to said heads, the diaphragm being drawn over the sides 70 of the block and glued or otherwise secured to the outer faces thereof, as seen in Figs. 3 and 4. By this means, as will be evident upon reference to Figs. 3 and 4, the diaphragm finds no resistance at the opposite 75 edges, being free to move with ease at these points, the body portion of the diaphragm being free to move throughout its area and giving greater lifting power and offering less resistance. Over the diaphragm and 80 the heads 36 are secured space bars 42. A boring 43 is formed through the upper edge of the block and connects with the boring 37. This serves, through the duct 14, to connect the pouch member and the rear of 85 the diaphragm to the tracker-duct. The blocks 34 may be cut from a channel strip of indefinite length; thus, there is a great advantage in manufacture.

In assembling the unit form of pouch 90 and exhaust valve plates 30 upon the wall 2, the plates 30 are centered with reference to the valve stem 31. The unit pouch members or primary pneumatics are applied thereto and each adjoining pair of pouch 95 members is held securely in place by a resilient plate 44 and a screw 45. A suitable strip 30^a of leather or the like, may be applied to the inner surface of the wall 2, and acts as an air seal for the plates 30. 100 The resilient plates 44 are cut away at their ends to clear the bleed holes of the pouches, and thus they bear upon the central line of the pouch members and appurtenant parts.

It will be obvious from the above that 105 all of the valve mechanisms are readily accessible upon removal of the front plate 3 of the action chest 1, and that any of the valves, pouch members, or appurtenant parts may be readily removed, replaced, or 110 examined with a minimum of inconvenience.

The striker pneumatics 16 are secured to the bars 18 and each has its movable board 16^a pivotally connected, as at 46, with a plunger 47, which, through an adjustable 115 member 48, actuates the corresponding wippen 49 of the piano action. The plungers 47 pass through perforated guides 47^a.

The operation of the mechanism is obvious. All of the valve actions, being located within the action or suction chest 1, are subject to the tension or suction of said chest, and the valves normally rest upon the seats of the suction ports 29. As soon as a tracker-duct is subjected to atmospheric pressure, the diaphragm of its pouch or primary pneumatic is subjected to the full suction of the chest and moves the valve 120 125

28, which instantly covers the atmospheric port 20, simultaneously opening the suction port 29, and subjects the striker or power pneumatic 16 to the suction of the chest. 5 The collapse of the power pneumatic actuates its corresponding wippen of the piano action. Upon closing of the tracker-duct, pressures are equalized on both sides of the diaphragm member 32 and the valve 28 is 10 re-seated, closing the suction port 29.

There is particular advantage in having the primary pneumatic formed as hereinabove described. Being of rectangular form, it has a greater area for a given size 15 block than would be possible with a circular diaphragm such as has been commonly used in pouch structures. It permits using a smaller block for a given maximum area of diaphragm. Furthermore, the circular 20 form of diaphragm is more limited as to its extent of movement, there is greater resistance owing to the cup-form of the chamber, and it tends to strain and pucker at the center. This results in the breaking down of 25 the diaphragm, causing almost constant renewals.

In the rectangular form, as defined, practically the whole surface of the diaphragm moves and gives a direct, firm thrust to the 30 valve stem. By using suitable spacing means as the spacing blocks 42, the entire surface of the diaphragm is opened to the suction of the chest, and there is ample space at the sides of the blocks for the passage 35 of air.

As illustrated, in the center of the diaphragm 32, there is a buffer disk 32^a which forms a staple base and wearing surface to bear against the buffer 31^a, mounted upon 40 the end of the valve spindle 31. In using the rectangular form of diaphragm, there is little or no tendency to throw off the buffer disk 32^a, which may be of a considerable size. Where a circular diaphragm is employed, there is constant trouble and annoyance due to the throwing off of the buffer 45 when one is used.

There are special advantages in the various features of construction and arrangement hereinabove set forth. The striker pneumatic may all be assembled upon their supporting members. The supporting members may be readily bored and assembled with reference to their sections and 50 with reference to the wall 2. The base-piece 55 17 may be easily and accurately formed and its valve pins may be arranged with precision. The boring of the valve chambers may be effected with harmony and the 60 parts upon the outer face of the board may be assembled or taken down with greatest facility. Similarly, the pouch or primary pneumatic units may be formed as complete structures and assembled upon the in-

ner face of the wall 2, with their valves 65 with the least possible inconvenience and trouble. Each individual part of the mechanism is thus made accessible and renewable, and the parts are interchangeable. It is obvious that the chest, as a whole, is very 70 much condensed inasmuch as the valve chambers and valves are located directly in one wall of the chest and that there is nothing extending within the chest except the pouch members and suction valve port 75 plates.

Another advantage is that I am able to obtain close coöperative relation between the valve and the pouch.

Modifications in details may be resorted 80 to without departing from the spirit of the invention or sacrificing any of its advantages.

What I claim as my invention and desire to secure by Letters Patent is:

1. In a device of the character described, the combination of a vacuum chamber casing, valve chambers formed in one wall of said casing, valves arranged in said chambers, primary pneumatics within the vacuum chamber for actuating said valves, said primary pneumatics removably secured to the wall of said chamber.

2. In a device of the character described, the combination of a vacuum chamber casing, valve chambers formed in one wall of said chamber, valves arranged in said chambers, primary pneumatics within the vacuum chamber for actuating said valves, said primary pneumatics removably secured to the wall of said chamber, striker pneumatics mounted upon the exterior wall of the chamber and ducts formed through the wall of the chamber directly connecting said striker pneumatics with said valve chambers.

3. In a device of the character described, the combination of a vacuum chamber, valve chambers formed in one wall of said chamber, valves arranged in said chambers, perforated plates partially covering said chambers and forming suction valve seats for the valves, primary pneumatics within the vacuum chamber mounted on said plates and coöperating with the valves for actuating the latter, and atmospheric ports extending through the wall of the casing.

4. In a device of the character described, the combination of a vacuum chamber casing, valve chambers formed in one wall of said chamber, suction ports connecting said chambers with a suction chamber, atmospheric ports formed through the wall of the vacuum chamber and providing atmospheric ports for the valve chambers, valves arranged in said valve chambers for controlling said ports, primary pneumatics arranged on the same wall of the chamber for

- controlling the valves, and striker pneumatics mounted exteriorly to the chamber and having ducts communicating with the valve chamber through the wall of the 5 vacuum chamber.
5. In a device of the character described, the combination of a vacuum chamber casting, valve chambers formed in one wall of said chamber, said valve chambers arranged 10 in a series of rows, atmospheric ports extending through the wall of the vacuum chamber to the valve chambers, supporting bars for striker or power pneumatics exteriorly mounted upon the wall of the 15 vacuum chamber and provided with a groove registering with a series of the atmospheric ports, striker pneumatics arranged upon one section of said supporting bars, one for each valve chamber, and connected therewith 20 through ducts formed in the bars and wall of the vacuum chamber, suction ports for the valve chambers opening to the vacuum chamber, and primary pneumatics within the vacuum chamber operatively associated 25 with the valve chambers and their valves, and valves within said valve chambers.
6. In a device of the character described, the combination of a vacuum chamber casting having valve chambers formed in one 30 wall of the casing and arranged in a series of tiers, supporting bars removably secured to the exterior of the wall, one for each tier, an atmospheric port for each of the valves formed through the wall of the casing, a 35 groove in the supporting bar registering with all the atmospheric ports of one tier of valves, valve pins secured to said supports and extending into the valve chambers, valves supported on said pins, suction ports 40 for said valves, primary pneumatics removably associated with said valves and arranged interiorly of the vacuum chamber, striker pneumatics one for each valve supported upon the supporting bars, and ducts 45 extending through said bars and the wall of the vacuum chamber for connecting the valve chambers and respective striker pneumatics.
7. In a device of the character described, 50 the combination of a vacuum chamber casting, valve chambers arranged in tiers and formed in one wall thereof, atmospheric ports for each of the valve chambers extending through said wall, removable perforated plates for each of said chambers providing suction port seats for the valves, primary pneumatics for actuating the valves removably secured to the wall and bearing against said plates, striker pneumatics exteriorly arranged to the wall, one for each 55 valve chamber, and ducts extending through the wall and connecting the valve chambers with the respective striker pneumatics.
8. In a device of the character described, 60 a vacuum chamber having a back wall and a removable front wall, valve chambers formed within the back wall, said chambers arranged in a series of tiers, atmospheric ports for the chambers extending through the back wall, sectional supporting bars, one for each 65 tier of valves arranged exteriorly of said wall, a groove in one section of each of said bars registering with the atmospheric ports of a tier of valve chambers, said groove communicating with the atmosphere, a valve pin for each valve chamber secured to the supporting bar, valves within the chambers mounted upon the pins, a removable plate for each valve chamber having a suction port, a primary pneumatic for each valve 70 arranged within the vacuum chamber and clamped against the plate, striker pneumatics supported on said sectional bars and in communication with the respective valve chambers, and tracker duct connections for each 75 of said primary pneumatics.
9. In a device of the character described, the combination of a vacuum chamber having a back wall and a removable front wall, a series of removable valve mechanisms arranged interiorly of the vacuum chamber and in tiers, sectional supporting bars secured to the exterior of the back wall, one for each tier of valve mechanisms, striker pneumatics mounted upon said sectional supporting bars, and registering openings in 80 said bars and the back wall communicating with the valve mechanisms, whereby the striker pneumatics are placed under exhaust or atmospheric pressures. 85
10. In a device of the character described, a vacuum chamber incased by a back wall, a removable front wall, base and end walls; valve mechanisms including primary pneumatics arranged within the chamber and 90 upon the back wall, and controlling striker pneumatics, the latter removably secured to the exterior of the back wall and controlled by the valve mechanisms, and a sectional head for the casing having registering 95 ducts, there being a duct for each valve mechanism, one section of the head having means for the attachment of tracker connections, and the other section of said head having means of connection with the primary pneumatics. 100
11. In a valve mechanism for pneumatically operated instruments, a primary pneumatic embodying a base piece and a diaphragm of substantially rectangular form 105 secured thereover with two edges secured thereto in one plane and the other edges unattached in said plane but affixed in another plane with portions practically free and unsupported, whereby minimum resistance is 110 provided, and means disconnected from the diaphragm and bearing against said base piece for supporting said primary pneumatic in operative position. 115
12. In a valve mechanism for pneumatic 120

- cally operated instruments, a base piece having projections at opposite ends forming a channel, a diaphragm secured to said projections and to the outer faces of the opposite sides of said base piece, means engaging said diaphragm at said projections, a member having a valve seat and a resilient member pressing said means against said first-named member.
- 10 13. In a valve mechanism for pneumatically operated instruments, a base piece with projections forming an open-ended channel, a diaphragm secured to said projections and overlapping the opposite edges of the base piece and secured thereto with substantially the entire area of the body portion free for movement, a plate having a valve seat, means interposed between said plate and portions of the diaphragm over said projections, and means holding said base piece and said means against said plate.
- 15 14. In a valve mechanism for pneumatically operated instruments, a base piece with a channel extended therethrough, said base piece having end projections, a diaphragm secured to said projections and overlapping the opposite edges of the base piece and secured thereto with substantially the entire area of the body portion free for movement, a plate having a valve seat, means interposed between said plate and portions of the diaphragm over said projections, and means bearing against the outer face of said base piece and removed from the diaphragm for sustaining the parts in position.
- 20 15. A primary pneumatic for valve actions comprising a block having a channel providing heads, an atmospheric connection to said channel, a bleed hole extending thereto, a diaphragm member extending over said heads and block and inclosing the channel, and a buffer centrally arranged with reference to said rectangular diaphragm.
- 25 16. A primary pneumatic for valve actions, comprising a base piece with a rectangular chamber therein and projections at opposite ends forming opposed walls of said chamber, said base piece being bored and having a boring through one end communicating with said boring, a diaphragm surrounding said chamber and secured to said projections and to the opposite sides of the base piece, with opposite portions supported in one plane and the other portions unattached in the same plane free and unsupported to reduce resistance and give greater lifting power to the diaphragm.
- 30 17. In a device of the character described, a vacuum chamber casing having an atmospheric port in one wall thereof, and a pneumatic-support on the outer wall of said casing having a groove communicating with said port and with the atmosphere.
- 35 18. In a device of the character described, a vacuum chamber casing having an atmospheric port and a valve chamber and a boring communicating therewith, and a pneumatic-support outside of said casing having a groove communicating with said port and with the atmosphere and an opening for affording communication between said boring and a power pneumatic.
- 40 19. In a device of the character described, a vacuum chamber casing with a plurality of atmospheric ports, and a pneumatic-support outside of said casing having a groove communicating with said port and with the atmosphere.
- 45 20. In a device of the character described, a vacuum chamber casing with a plurality of atmospheric ports, a pneumatic-support outside of said casing having a groove communicating with said ports and with the atmosphere, and valve guiding pins mounted in said support and extending into said ports.
- 50 21. In a device of the character described, a vacuum chamber casing with a plurality of atmospheric ports, a pneumatic-support outside of said casing having a groove communicating with said ports and with the atmosphere, and valve guiding means extended through said ports.
- 55 22. In a device of the character described, a vacuum chamber casing with a plurality of atmospheric ports, a pneumatic-support outside of said casing having a groove communicating with said ports and with the atmosphere, and valve guiding means in said support.
- 60 23. In a device of the character described, the combination of a vacuum chamber casing, valve chambers formed in one wall of said casing, valves arranged in said chambers and primary pneumatics within the vacuum chamber and supported independently of one wall thereof for actuating said valves.
- 65 24. An action chest having a vacuum chamber with a back board, and a removable front board, and valve seats and diaphragms within the vacuum chamber and supported entirely independently of the front board.
- 70 25. An action chest having a vacuum chamber with a back board, and a removable front board, and valve seats and diaphragms within the vacuum chamber and supported entirely independently of the front board, said back board having valve chambers, and valves therein.
- 75 26. An action chest having a vacuum chamber with a back board, and a removable front board, and valve seats and diaphragms within the vacuum chamber secured to the back board and supported entirely independently of the front board.
- 80 27. An action chest having a vacuum chamber, with a back board and a removable front board, valve seats, and diaphragms within

said chamber and holding said seats to the back board independently of the front board.

28. An action chest having a vacuum chamber, with a back board and a removable front board, valve seats, and diaphragms within said chamber and holding said seats to the

back board independently of the front board, there being a space between said diaphragms and seats.
